CLAIM

The ornamental design for a recording medium, as shown and described.

DESCRIPTION

FIG. 1 is a front perspective view of a recording medium, showing my new design;

FIG. 2 is a front elevational view thereof; the opposite side being a mirror image thereof;

FIG. 3 is a top plan view thereof;

FIG. 4 is a bottom plan view thereof;

FIG. 5 is a left side elevational view thereof; the opposite side being a mirror image thereof;

FIG. 6 is a perspective view thereof with a cap in a removed state for completeness of illustration;

FIG. 7 is a front elevational view thereof, shown without a cap for completeness of illustration; the opposite side being a mirror image thereof;

FIG. 8 is a left side elevational view of FIG. 7; the opposite side being a mirror image thereof; and,

FIG. 9 is a bottom plan view of FIG. 7; and the top plan view of FIG. 7 being identical with the FIG. 3.
